KR 300622729.0000 * 11/2011
 WO WO-D036467-045 * 7/1996*Primary Examiner* — Karen E Eldridge Powers(74) *Attorney, Agent, or Firm* — Downs Rachlin Martin PLLC(57) **CLAIM**

The ornamental design for a nail brush base, as shown and described.

DESCRIPTION

FIG. 1 is a perspective view of an embodiment of a nail brush base showing my new design;

FIG. 2 is a side elevation view thereof;

FIG. 3 is another side elevation view thereof;

FIG. 4 is an end elevation view thereof;

FIG. 5 is another end elevation view thereof;

FIG. 6 is a top plan view thereof; and,

FIG. 7 is a bottom plan view thereof.

The dash-dash-dash type broken lines in the Figures are for the purpose of illustrating unclaimed portions of the nail brush base and form no part of the claimed design.

1 Claim, 2 Drawing Sheets(56)
